COMMUNICATIONS SYSTEM COMPRISING A MATRIX NETWORK OF MODULATION ELEMENTS

The invention relates to a device for the transmission of information signals, which device is provided with an information source, a carrier oscillator, a modulator and a shift register connected to the information source and having a plurality of shift register elements whose contents are shifted by means of a control generator.

A device for the transmission of binary pulses which occur in the rhythm of a clock frequency and in which the shift register elements of a digitally constructed shift register are connected to a combination device through weighting networks, has special advantages for the transmission of these pulsatory signals (compare U.S. Pat. application Ser. No. 594,615, filed Nov. 1966 now U.S. Pat. No. 3,500,215. By suitable proportioning of the weighting networks a filter is obtained which satisfies all requirements for pulse transmissions in which filter not only the desired amplitude-versus-frequency characteristics but also the linear phase-versus-frequency characteristic required for pulse transmission can be realized in a simple manner, while in addition transfer characteristics once adjusted optimally, for example, in accordance with the Nyquist criteria for preserving equidistant zero crossings in the received signal, remain unchanged due to a fixed coupling between clock frequency and shift frequency even in case of varying operating conditions such as variations in the clock frequency.

Furthermore, similar filters provided with shift registers may be used in the transmission of continuous information signals (analog signals), which analog signals are first converted in an analog-to-digital converter into binary pulse series in accordance with a certain code. After the filtering process in the shift register provided with weighting networks, a decoding of the filtered pulse series follows so that the analog signal filtered in accordance with the desired transfer characteristic occurs at the output of the decoder (compare patent application Ser. No. 619,324, filed Feb. 28, 1967, now U.S. Pat. No. 3,521,170.

Such filters which are provided with shift registers and weighting networks are, however, alternatively suitable for more general use in the transmission of information with the aid of pulse-modulated carrier oscillations if, as described in patent application Ser. No. 728,706, filed May 13, 1968 the pulses to be transmitted are modulated in a digital modulator on a rectangularly shaped carrier oscillation whose frequency is equal an integral multiple of half the clock frequency. When using an arbitrary modulation method, for example, amplitude modulation, phase modulation or frequency modulation, the desired transmission mode may then be adjusted, for example, double sideband transmission, vestigial sideband transmission or single sideband transmission. It is even possible in these devices to completely correct the influence of the unwanted modulation products located within the frequency band to be transmitted by using a correction network, if the carrier frequency is equal to said integral multiple of half the clock frequency, so that a pulse transmission of optimum quality is achieved (compare patent application Ser. No. 840,409 filed July 9, 1969, now U.S. Pat. No. 3,611,143.

Such devices for the transmission of information signals can be obtained with the aid of logic circuits without using reactive elements and are therefore particularly suitable for complete integration in a semiconductor body, while a structure of the device as described in patent application Ser. No. 19,437, filed Mar. 13, 1970 now U.S. Pat. No. 3,624,427 provides great reliability of operation and substantial suppression of unwanted phenomena, for example, reactive effects, cross talk and interferences as a result of mutual differences between components of the circuit, so that a pulse transmission of optimum quality is obtained even at pulse frequencies of many MHz.

It is an object of the present invention to provide a different concept of a transmission device of the kind described in the preamble in which all advantages of the devices described hereinbefore are maintained in combination and in which par-

ticularly a general usability is obtained, while in addition the freedom of choice of the carrier frequency is considerably enhanced while yet preventing unwanted modulation products from occurring in the frequency band to be transmitted.

According to the invention the transmission device is characterized in that the carrier oscillator is also connected to a shift register having a plurality of shift register elements whose contents are shifted by means of a control generator, while the transmission device is furthermore provided with a matrix network whose nodes incorporate modulation elements, the input circuits of which are connected to both the shift register elements in which the information signals are shifted and to the shift register elements in which the carrier signals are shifted, while weighting devices are connected to the output circuits of the modulation elements, the different weighting devices being connected to a common combination device the output of which constitutes the output of the transmission device.

In this respect it is to be noted that a matrix network is understood to mean a grid comprising at least two rows and two columns. The shift registers used may be constituted both by digital technique shift registers are built up from a plurality of bistable triggers, and by analog technique shift registers built up from a plurality of capacitive storage elements (capacitive shift register); in both cases the contents of the shift register elements are shifted in a rhythm corresponding to the frequency of the control generator, so that dispersion of the signals stored in the shift registers does not occur. Logic circuits are preferably used as modulation elements, particularly selection gates such as, for example, AND-gates, OR-gates and Exclusive OR-gates (modulo-2-adders).

In order that the invention may be readily carried into effect a few embodiments thereof will now be described in detail by way of example with reference to the accompanying diagrammatic drawings, in which:

FIG. 1 shows a device according to the invention which is constructed as a modulator in a transmission system for binary synchronous information pulses;

FIG. 2 shows a few time diagrams to explain the operation of the device shown in FIG. 1;

FIG. 3 shows a few frequency diagrams to explain the operation of the device of FIG. 1;

FIG. 4 shows the envelope of the frequency spectrum of a vestigial sideband signal generated with the aid of the device of FIG. 1;

FIG. 5 shows a modification of the device of FIG. 1 for generating single sideband signals by means of pseudoternary coding;

FIG. 6 shows a modification of the device of FIG. 1 provided with an additional attenuation network;

FIG. 7 shows a modification of the device of FIG. 1 for generating frequency-modulated signals;

FIG. 8 shows a few time diagrams to explain the operation of the device shown in FIG. 7;

FIG. 9 shows a modification of the device of FIG. 1 for generating orthogonal signals;

FIG. 10 shows a block diagram of the function unit which underlies the operation of the device according to the invention;

FIG. 11 shows a parallel arrangement of several function units in accordance with FIG. 10;

FIG. 12 shows a few frequency diagrams to explain the operation of the device shown in FIG. 1 as an amplitude modulator;

FIG. 13 shows a few suitable frequency characteristics for generating pseudoternary coded pulse series with which single sideband modulation in accordance with the phase method is possible;

FIG. 14 shows a function diagram of the device of FIG. 7 for generating frequency-modulated signals;

FIG. 15 shows a function diagram for the function unit which underlies the operation of the device according to the invention, provided with an arbitrary number of shift registers;

FIG. 16 shows a function diagram of a technically important configuration of the device according to the invention;

FIG. 17 shows a diagram of the principle for generating time-delayed functions;

FIG. 18 shows a function diagram of a device according to the invention, provided with three shift registers for generating single sideband signals;

FIG. 19 shows a diagram of the embodiment of the device of FIG. 18 for generating single sideband signals;

FIG. 20 shows the block diagram of the known N-path-filter ($N=3$);

FIG. 21 shows the function diagram of the N-path-filter according to the invention;

FIG. 22 shows the diagram of the embodiment of the function diagram of FIG. 21 of an N-path-filter;

FIG. 23 shows a device according to the invention for generating a carrier frequency raster;

FIG. 24 shows a frequency diagram to explain the device of FIG. 23.

FIG. 1 shows the modulator of a transmission system for binary synchronous information pulses. The frequency band to be used lies, for example, between 300 and 3300 Hz, while the transmission speed is, for example, 1200 Baud. The instants of occurrence of the binary information pulses originating from an information source 1 coincide with the pulses of a series of equidistant clock pulses which are provided by a clock-pulse generator 2 at a repetition frequency f_T of, for example, 1,200 Hz. The information pulses are applied to a shift register 4 which consists of a plurality of shift register elements 5, 6, 7, 8, 9, 10, 11, 12, 13 and 14. The shift frequency f_r of the shift register 4 is equal to an integral multiple of the clock frequency f_T of the clock pulse generator 2 and is generated with the aid of a control generator coupled to the clock pulse generator 2 and formed as a multiplier 3. The shift frequency f_r is, for example, twice the clock frequency f_T and equals 2,400 Hz.

The carrier oscillator in the form of a carrier pulse generator 15 provides a series of equidistant carrier pulses which are applied to a shift register 17 having a plurality of shift register elements 18, 19, 20, 21, 22, 23, 24, 25, 26 and 27. The carrier pulse frequency f_c is, for example, 1,800 Hz. The shift frequency f_r of shift register 17 is an integral multiple of the carrier frequency f_c of the carrier pulse generator 15 and is likewise generated with the aid of a control generator coupled to the carrier pulse generator 15 and formed as a multiplier 16. The shift frequency f_r is, for example, 10 times higher than the carrier frequency f_c and equals 18 kHz.

The output circuits of the shift register elements of both shift registers 4 and 17 are connected to a matrix network 28. In this matrix network 28 the nodes of the output circuits of the shift register elements of both shift registers 4 and 17 include modulation elements 30 through 150 which establish a logic combination of the stored binary pulses. The output signals of the modulation elements 30-150 are weighted with the aid of weighting networks constituted by attenuation networks 151 through 271 and a combination device 29. The sum of the weighted output signals of the modulation elements 30-150 then occurs at an output 272 of the combination device 29.

To explain the operation of the device of FIG. 1 in greater detail, FIG. 2 shows a few time diagrams.

The curve *a* shows an arbitrarily chosen series of information pulses 1101 at the output of information source 1. The pulse duration $T = 1/f_T$ of an information pulse and likewise the storage period $\tau = 1/f_r$, which is equal to the time interval between successive shift pulses controlling the shift register 4, are shown in FIG. 2. The curve *b* shows the series of carrier pulses of the carrier pulse generator 15. The storage period $\delta = 1/f_r$, which is equal to the time interval between successive shift pulses controlling shift register 17, is likewise shown in FIG. 2. The curves *c* and *d* show the input signals of the modulation element 48 which is chosen as an arbitrary example. In this case curve *c* can be recognized as the pulse series *a* delayed over a period τ and curve *d* as the pulse series *b*

delayed over a period 3δ . In the case of a multiplicative combination of the input signals *c* and *d* the modulation element 48 formed as a selection gate, in this case an AND-gate, provides the output signal shown at *e* in FIG. 2. The sum of the output signals weighted by the weighting networks 151, 29 through 271, 29 then occurs at the output 272. The higher frequency components which are already greatly suppressed in the output signal at the output 272 are eliminated by the frequency characteristic of the transmission path or, optionally, by the interposition of a very simple bandpass filter.

The nature of the output signal depends on the choice of the weighting networks. The transfer coefficient $C_{\nu\mu}$ from the output of a modulation element to the output 272 is determined by the attenuation network connected to the modulation element and the network 29 functioning as a combination device, in which ν indicates a shift register element of shift register 4, reckoned from the center of the shift register 4 and with opposite sign on either side of this center, while μ likewise indicates a shift register element of shift register 17 reckoned from the center of shift register 17 and with opposite sign on either side of this center. Thus, for example, the transfer coefficient from the modulation element 31 to output 272 (determined by the networks 152 and 29) is indicated by C_{-3+4} , from modulation element 60 to output 272 by C_{-3-3} , from modulation element 150 to 272 by $C_{117-5-5}$ etc.

If the transfer coefficients are proportioned, for example, in accordance with the equations:

$$C_{\nu\mu} = \begin{cases} 4 \frac{\omega_g}{\omega_r} \cdot \frac{\omega_c}{\omega_b} \cdot \sin \left(\nu 2\pi \frac{\omega_g}{\omega_r} \right) \cdot \cos \left(\mu 2\pi \frac{\omega_c}{\omega_b} \right), & |\mu| < \frac{\omega_b}{2\omega_c} \\ 2 \frac{\omega_g}{\omega_r} \cdot \frac{\omega_c}{\omega_b} \cdot \sin \left(\nu 2\pi \frac{\omega_g}{\omega_r} \right) \cdot \cos \left(\mu 2\pi \frac{\omega_c}{\omega_b} \right), & |\mu| = \frac{\omega_b}{2\omega_c} \\ 0, & |\mu| > \frac{\omega_b}{2\omega_c} \end{cases} \quad (1)$$

$$\begin{aligned} \nu &= 0, \pm 1, \pm 2, \dots, \pm n \\ \mu &= 0, \pm 1, \pm 2, \dots, \pm m \end{aligned} \quad (2)$$

in which $\sin(x)$ is the abbreviated notation for $(\sin\phi)/\phi$, the amplitude-modulated signal qualitatively shown by curve *f* in FIG. 2 is obtained, as will be proved mathematically hereinafter with the aid of Fourier transform techniques. To realize both positive and negative transfer coefficients $C_{\nu\mu}$ the modulation elements 30 through 150 are provided with complementary outputs.

For the embodiment shown in FIG. 1, there applies: $n = m = 5$. The radial frequency $\omega_b = 2\pi f_b$ indicates half the bandwidth of the AM-signal. Further to the exemplary values $f_g = \omega_g/2\pi = 2,400$ Hz, $f_c = \omega_c/2\pi = 18$ kHz and $f_r = \omega_r/2\pi = 1,800$ Hz, the value of 600 Hz is found for the 3 dB bandwidth f_{3dB} .

If the equation:

$$\omega_b/2\omega_{3dB}, i = 1, 2, 3, \dots \quad (3)$$

IS satisfied, an optimum suppression of the harmonics of the carrier frequency is obtained. For the values given in the present example the harmonics of the carrier frequency of the order 1 to 7 inclusive and the associated frequency bands are completely suppressed, as will be explained hereinafter. Consequently, at a carrier frequency of 1,800 Hz a greatly reduced component only occurs at 16.2 kHz.

The phenomena in the frequency range will be explained with reference to FIG. 3. The envelope of the spectrum $F_1(\omega)$ is shown at *a* for an arbitrary series of information pulses having a pulse duration $T = 1/f_T$ which pulses are derived from the information source 1. An amplitude-modulated signal whose spectrum has the envelope shown at *b* in FIG. 3 then appears at the output 272 of the device. In this case it is assumed that half the bandwidth ω_b corresponds to $\omega_r/2$. If the frequency components located outside the information band and being, as already described, greatly suppressed are eliminated by the frequency characteristic of the transmission path or by the incorporation of a simple bandpass filter, then this leads to an

envelope of the AM-signal having a shape as shown at c in FIG. 3. Such a signal may be demodulated by known methods which will not be further referred to.

The modulation process and the filtering process in the device according to the invention take place without using reactive elements in this device, that is to say, only active elements and resistors are used. Consequently, this device is particularly suitable for integration in a semiconductor body, while in addition unwanted modulation products and harmonics are greatly suppressed. The device according to the invention is distinguished from the known devices by its striking advantage that unwanted modulation products do not occur at all within the frequency band to be transmitted, which up till now has not been the case in the known devices. On the one hand there is great freedom in the choice of the repetition frequency of the information pulses and the carrier pulses, while on the other hand it is possible to completely eliminate the unwanted modulation products, which are already greatly suppressed, by extending the number of shift register elements.

The device according to the invention is not only distinguished by the advantages mentioned hereinbefore, but also by its general application. Particularly a variation in the transfer coefficient $C_{\nu\mu}$ optionally together with a variation in the type of selection gate used as a modulation element makes it possible to adjust to any modulation mode, for example, phase modulation, vestigial sideband modulation, single sideband modulation, frequency modulation or orthogonal modulation, as will now be further described with reference to FIGS. 5 - 9. The prescriptions for proportioning will be mathematically derived hereinafter.

It is alternatively possible to generate a vestigial sideband signal with a device as shown in FIG. 1. To this end only the transfer coefficients $C_{\nu\mu}$ are to be varied:

$$C_{\nu\mu} = \begin{cases} 4 \frac{\omega_g}{\omega_r} \cdot \frac{\omega_c}{\omega_\delta} \cdot \left[\text{si} \left(\nu 2\pi \frac{\omega_g}{\omega_r} \right) \cdot \cos \left(\mu 2\pi \frac{\omega_c}{\omega_\delta} \right) \pm \text{ci} \left(\nu 2\pi \frac{\omega_g}{\omega_r} \right) \cdot \sin \left(\mu 2\pi \frac{\omega_c}{\omega_\delta} \right) \right], & |\mu| < \frac{\omega_\delta}{2\omega_c} \\ 2 \frac{\omega_g}{\omega_r} \cdot \frac{\omega_c}{\omega_\delta} \cdot \left[\text{si} \left(\nu 2\pi \frac{\omega_g}{\omega_r} \right) \cdot \cos \left(\mu 2\pi \frac{\omega_c}{\omega_\delta} \right) \pm \text{ci} \left(\nu 2\pi \frac{\omega_g}{\omega_r} \right) \cdot \sin \left(\mu 2\pi \frac{\omega_c}{\omega_\delta} \right) \right], & |\mu| = \frac{\omega_\delta}{2\omega_c} \\ 0, & |\mu| > \frac{\omega_\delta}{2\omega_c} \end{cases} \quad (4)$$

$$C_{\nu\mu} = \begin{cases} \frac{4}{\pi} \frac{\omega_g}{\omega_r} \cdot \frac{\omega_c}{\omega_\delta} \left[\frac{1 + \cos \left(\nu 2\pi \frac{\omega_g}{\omega_r} \right)}{1 - \left(2\nu \frac{\omega_g}{\omega_r} \right)^2} \cdot \cos \left(\mu 2\pi \frac{\omega_c}{\omega_\delta} \right) \pm \frac{\sin \left(\nu 2\pi \frac{\omega_g}{\omega_r} \right)}{1 - \left(2\nu \frac{\omega_g}{\omega_r} \right)^2} \cdot \sin \left(\mu 2\pi \frac{\omega_c}{\omega_\delta} \right) \right], & |\mu| < \frac{\omega_\delta}{2\omega_c} \\ \frac{2}{\pi} \frac{\omega_g}{\omega_r} \cdot \frac{\omega_c}{\omega_\delta} \left[\frac{1 + \cos \left(\nu 2\pi \frac{\omega_g}{\omega_r} \right)}{1 - \left(2\nu \frac{\omega_g}{\omega_r} \right)^2} \cdot \cos \left(\mu 2\pi \frac{\omega_c}{\omega_\delta} \right) \pm \frac{\sin \left(\nu 2\pi \frac{\omega_g}{\omega_r} \right)}{1 - \left(2\nu \frac{\omega_g}{\omega_r} \right)^2} \cdot \sin \left(\mu 2\pi \frac{\omega_c}{\omega_\delta} \right) \right], & |\mu| = \frac{\omega_\delta}{2\omega_c} \\ 0, & |\mu| > \frac{\omega_\delta}{2\omega_c} \end{cases} \quad (5)$$

In this equation $\text{ci}(\phi)$ is an abbreviated notation for the function $(1 - \cos \phi)/\phi$. If the positive sign is chosen in Equation (4), the lower sideband is produced; in the other case the upper sideband is produced as a resulting signal. FIG. 4 shows the envelope of the vestigial sideband signal in the last-mentioned situation. Also in this case the Equations (2) and (3) apply. As will be referred to hereinafter, the generated vestigial sideband signal changes into a single sideband signal upon

increasing values of m and n .

FIG. 5 shows a modification of the device of FIG. 1 for generating a single sideband signal having comparatively small values of m and n in which the elements corresponding to those in FIG. 1 have the same reference numerals in FIG. 5. As already described, for example, in the U.S. Pat. application Ser. No. 532,744, filed Mar. 8, 1969 or in the article by P. Leuthold and F. Tisi, "Ein Einseitenbandsystem für Datenubertragung" (Archiv der Elektrischen Übertragung 21 (1967) Vol. 7, pages 354-362) it is recommendable for single sideband modulation systems for binary information pulse series to subject the series of information pulses to a code conversion prior to the modulation process during which the original series of binary information pulses is converted into a series of likewise binary information pulses in such a manner that a three-level signal is produced in the receiver after demodulation of the single sideband signal, which three-level signal is converted into the original series of binary information pulses by means of full-wave rectification. Such a binary code conversion is efficiently achieved by means of a transformation element 273 whose output signal is constituted by modulo-2-addition of the information pulses delayed over a period of time kT wherein k is an integer and T is the pulse duration of an information pulse. The number k preferably chosen to be equal to 2. Such a code conversion is alternatively achieved by using twice change-of-state modulation (binary differential modulation) on the series of information pulses. It is then found that the same code conversion is obtained generally for $k=2^n$, wherein n is an integer, as when applying k times binary change-of-state modulation on the series of information pulses. Single sideband modulation and filtering are carried out in the matrix network 28. The transfer coefficients $C_{\nu\mu}$ must then be chosen in accordance with the equation below which will be derived hereinafter:

Also in this case the lower sideband or the upper sideband is produced dependent on the choice of the sign in Equation (5) for the transfer coefficients (positive or negative). The bandwidth ω_g of the single sideband signal then becomes equal to half the clock frequency $\omega_r/2$ of the information pulses.

FIG. 6 shows a modification of the device of FIG. 1, for generating a phase-modulated signal in which elements corresponding to those in FIG. 1 have the same reference nu-

merals. In the device according to FIG. 6, a series of carrier pulses having a suitably chosen amplitude and phase is subtracted from the amplitude-modulated signal which is generated by means of the matrix network 28, having transfer coefficients $C_{\nu\mu}$ in accordance with Equation (1) so that a phase-modulated signal results. To this end, the attenuation network 274 through 284 are additionally connected to the output circuits of the shift register 17. The transfer coefficients C_{μ} from the output circuits of shift register 17 to the modulator output 272 which are determined by the networks 274, 29 through 284, 29 are to be proportioned as follows:

$$C_{\mu} = \begin{cases} -\frac{1}{2} \frac{\omega_c}{\omega_b} \cdot \cos \left(\mu 2\pi \frac{\omega_c}{\omega_b} \right), & |\mu| < \frac{\omega_b}{2\omega_c} \\ -\frac{1}{2} \frac{\omega_c}{\omega_b} \cdot \cos \left(\mu 2\pi \frac{\omega_c}{\omega_b} \right), & |\mu| = \frac{\omega_b}{2\omega_c} \\ 0, & |\mu| > \frac{\omega_b}{2\omega_c} \end{cases} \quad (6)$$

In accordance with equation (2) there applies that:

$$\mu = 0, \pm 1, \pm 2, \dots, \pm n \quad (7)$$

The modulation elements 30-150 in the device according to FIG. 1 may not only be formed as AND-gates but also modulo-2 adders (Exclusive OR-gates). If the transfer coefficients are then proportioned invariably in accordance with Equation (1) the same phase-modulated signal as that in the device of FIG. 6 is produced at the output 272. For this case the output signal of modulation element 48 is denoted at g in FIG. 2. This refers to the modulo-2 addition of the input signals shown at c and d in FIG. 2 in which, as is apparent from FIG. 2, the series of carrier pulses d are phase-modulated by the series of information pulses c . The sum of the output signals of the modulation elements weighted in the matrix network 28 produces the phase-modulated signal shown at h in FIG. 2 after elimination of the higher frequency components.

The device according to the invention may alternatively be used for producing a frequency-modulated signal. FIG. 7 shows the device used for this purpose, in which the elements corresponding to those of FIG. 1 have the same reference numerals. For the logic combination in the nodes of the matrix network 28, modulo-2-addition is used. As will be proved mathematically hereinafter, the transfer coefficients $C_{\nu\mu}$ are chosen in accordance with Equation (4). The series of binary information pulses provided by the information source 1 is applied to an OR-gate 285 the second input circuit of which is connected to a subcarrier pulse generator 286. This generator provides a series of subcarrier pulses the repetition frequency of which is equal to ω_b . FIG. 8 shows the time diagrams of the input and output signals of the OR-gate 285 at arbitrarily chosen ratio of the two carrier frequencies. The uniform series of pulses b from the generator 286 is logically added to the series of information pulses a . As a result a new pulse series c is produced which is applied to the shift register 4.

If the conditions

$$\omega_b/\omega_r = 2, 3, 4, \dots \quad (8) \text{ and}$$

$$\omega_r/\omega_b = 1, 2, 3, \dots \quad (9)$$

are satisfied, a frequency-modulated signal is produced at the output 272 of the modulator, the frequency of said signal varying between the values ω_c and $\omega_c - \omega_b$ or between the values ω_c and $\omega_c + \omega_b$ dependent on whether the negative or the positive sign is chosen in Equation (4). After elimination of the higher frequency components the frequency-modulated signal shown qualitatively at i in FIG. 2 is produced.

To generate the same frequency-modulated signal the device according to FIG. 6 may alternatively be used in which the modulation elements 30-150 are formed as AND-gates if the transfer coefficients $C_{\nu\mu}$ are chosen in accordance with Equation (4) and if the additional transfer coefficients C_{μ} are chosen in accordance with Equation (6). If the OR-gate 285 and the subcarrier pulse generator 286 connected thereto is incorporated between the information source 1 and the shift register 4 in the manner as shown in FIG. 7, the same frequen-

cy-modulated signal as that at the output 272 of the device of FIG. 7 is produced at the output 272.

FIG. 9 shows a device for orthogonal modulation. To this end the series of information pulses or from the two information sources 1 and 287 are modulated on carriers in phase quadrature. In most practical situations the information source 287 may be controlled by the clock pulse generator 2; in this case the use of a clock pulse generator 288 is economized. The same applies to the multiplier 289; the shift register 290 is then controlled by means of the output signal from the multiplier 3. In this case the modulation elements of the two matrix networks 28 and 291 are simultaneously controlled by the shift register elements of the shift register 17 connected to the carrier pulse generator 15.

15 The transfer coefficients $C_{\nu\mu}$ of the matrix network 28 are proportioned in accordance with Equation (1). The coefficients $C_{\nu\eta}$ of the matrix network 291 which are defined in the same manner as the coefficients of the matrix network 28 are to be chosen in accordance with the prescription:

$$20 \quad C_{\kappa\lambda} = \begin{cases} 4 \cdot \frac{\omega_b}{\omega_r} \cdot \frac{\omega_c}{\omega_b} \cdot \sin \left(\kappa 2\pi \frac{\omega_b}{\omega_r} \right) \sin \left(\lambda 2\pi \frac{\omega_c}{\omega_b} \right), & |\lambda| < \frac{\omega_b}{2\omega_c} \\ 2 \cdot \frac{\omega_b}{\omega_r} \cdot \frac{\omega_c}{\omega_b} \cdot \sin \left(\kappa 2\pi \frac{\omega_b}{\omega_r} \right) \sin \left(\lambda 2\pi \frac{\omega_c}{\omega_b} \right), & |\lambda| = \frac{\omega_b}{2\omega_c} \\ 0, & |\lambda| > \frac{\omega_b}{2\omega_c} \end{cases} \quad (10)$$

30 with

$$\kappa = 0, \pm 1, \pm 2, \dots, \pm k \quad (11)$$

$$\lambda = 0, \pm 1, \pm 2, \dots, \pm l$$

35 Here it is assumed that the radial shift frequency of the shift registers 4 and 290 is equal as is half the bandwidth ω_r of both channels. If the input signals in the modulation elements are combined in a multiplicative manner, the desired orthogonally modulated signal occurs at the output 272.

40 Together with the described advantages of the device according to the invention, namely a structure suitable for integration in a semiconductor body, great suppression of unwanted modulation products as well as general possibilities of use, the invention has the surprising property that the device according to the invention can be dealt with mathematically in a simple and convenient manner with the aid of the function unit shown in FIG. 10. The starting point for dealing with this device is constituted by linear, passive, time-invariant net-

45 works 292 and 293 having pulse response $f_1(t)$ and $f_2(t)$ in which the time functions $f_1(t)$ and $f_2(t)$ are applied in the form of electrical voltages or currents to the input circuits. The output signals $f_{11}(t)$ and $f_{22}(t)$ of both networks are applied to a modulator 294 which produces a function $F(t)$ therefrom.

50 A multiplicative combination of the filtered signals $f_{11}(t)$ and $f_{22}(t)$ is effected in the modulator 294:

$$F(t) = f_{11}(t) \cdot f_{22}(t) \quad (12)$$

55 with

$$f_{11}(t) = \int_{-\infty}^{\infty} f_1(t - \tau_1) h_1(\tau_1) d\tau_1 \quad (13)$$

60 and

$$f_{22}(t) = \int_{-\infty}^{\infty} f_2(t - \tau_2) h_2(\tau_2) d\tau_2 \quad (14)$$

65 70 there follows from Equation (12) the relation:

$$75 \quad F(t) = \int_{-\infty}^{\infty} \int_{-\infty}^{\infty} h_1(\tau_1) h_2(\tau_2) f_1(t - \tau_1) f_2(t - \tau_2) d\tau_1 d\tau_2 \quad (15)$$

By parallel arrangement of several networks in accordance with FIG. 10, the more general configuration as shown in FIG. 11 is obtained for which the following relation applies:

$$F(t) = \int_{-\infty}^{\infty} \int_{-\infty}^{\infty} h(\tau_1, \tau_2) f_1(t-\tau_1) f_2(t-\tau_2) d\tau_1 d\tau_2 \quad (16)$$

The function $h(\tau_1, \tau_2)$ can then be calculated from:

$$h(\tau_1, \tau_2) = h_1(\tau_1) h_2(\tau_2) + h_3(\tau_1) h_4(\tau_2) + \dots + h_{n+1}(\tau_1) h_n(\tau_2) \quad (17)$$

The physical interpretation of the right-hand member of Equation (16) directly leads to the representation that the functions $f_1(t)$ and $f_2(t)$ are each stored in an ideal delay line and that partial signals are derived from the delay lines at infinitesimal mutual distances. Each partial signal of a delay line is multiplied by all partial signals of the other delay line and weighted by a weighting factor in accordance with the function $h(\tau_1, \tau_2)$. The integration indicates that the partial signals thus weighted are added.

Since the functions $f_1(t)$ and $f_2(t)$ are not known for negative values of time, a fictitious zero point in the past must be determined. In this manner a general signal delay is introduced which, however, does not play a role in transmission systems. Furthermore, delay lines having a finite delay only can be achieved in practice. This means that the limits of the integrals in Equation (16) are finite and thus $F(t)$ is only obtained at an approximation. If a further approximate error is admitted, the integration may be replaced by an addition:

$$F(t) = \sum_{\mu=-m}^m \sum_{\nu=-n}^n T_1 T_2 h(\nu T_1, \mu T_2) f_1(t-\nu T_1) f_2(t-\mu T_2) \quad (18)$$

This expression shows that the two ideal delay lines must be tapped in discrete places which are spaced over equidistant time intervals T_1, T_2 , but which can be achieved very accurately with the aid of shift registers. Each signal thus tapped from one shift register is multiplied by all other signals tapped from the other shift register. The resultant products are provided with a weighting factor in accordance with the coefficients:

$$C_{\nu\mu} = T_1 T_2 h(\nu T_1, \mu T_2) \quad (19)$$

and are finally added. For signals $f_1(t)$ and $f_2(t)$ in the form of synchronous rectangular pulses a capacitive shift register may be used as a shift register, a single or multilevel digital shift register may be used for binary or multilevel pulses. Analog signals $f_1(t)$ and $f_2(t)$ may be converted into such pulse series optionally by using a sampler.

To gain a better understanding of the modulation process of the system, Equation (18) is subjected to a Fourier transformation while using Equation (19):

$$\phi(\omega) = \frac{1}{2\pi} \sum_{\mu=-m}^m \sum_{\nu=-n}^n C_{\nu\mu} \exp(-j\nu T_1 \omega) F_1(\omega) \star \exp(-j\mu T_2 \omega) F_2(\omega) \quad (20)$$

In this equation $\phi(\omega)$, $F_1(\omega)$ and $F_2(\omega)$ indicate the Fourier transformations of the functions $F(t)$, $f_1(t)$ and $f_2(t)$. The symbol $\star$ denotes the convolution operation.

In the case of the basic system in accordance with FIG. 10, Equation (20) may be written as

$$\phi(\omega) = \frac{1}{2\pi} \sum_{\nu=-n}^n C_{\nu} \exp(-j\nu T_1 \omega) F_1(\omega) \star \sum_{\mu=-m}^m C_{\mu} \exp(-j\mu T_2 \omega) F_2(\omega) \quad (21)$$

The coefficients C_{ν} and C_{μ} then satisfy the relations:

$$C_{\nu\mu} = C_{\nu} C_{\mu} \quad (22)$$

$$C_{\nu} = T_1 h_1(\nu T_1) \quad (23)$$

$$C_{\mu} = T_2 h_2(\mu T_2) \quad (24)$$

It will readily be evident that in these equations C_{ν} and C_{μ} represent the coefficients of the Fourier expansions of the transfer functions $H_1(\omega)$ and $H_2(\omega)$ which magnitudes can be

calculated as the Fourier transformations of the pulse responses $h_1(t)$ and $h_2(t)$. The periodicity of the Fourier series $\tilde{H}_1(\omega)$ and $\tilde{H}_2(\omega)$ is given by the radial frequencies $\omega_{p1} = 2\pi/T_1$ and $\omega_{p2} = 2\pi/T_2$, respectively.

Consequently, Equation (21) may be written as:

$$\phi(\omega) = 1/(2\pi) \tilde{H}_1(\omega) F_1(\omega) \star \tilde{H}_2(\omega) F_2(\omega) \quad (25)$$

The device including two tapped shift registers in which the signals derived from the taps are multiplied, weighted and added together thus indeed has the properties of the system shown in FIG. 10. However, the fact must be taken into account that the transfer functions $\tilde{H}_1(\omega)$ and $\tilde{H}_2(\omega)$ are periodic, while the periodicity may freely be chosen by the proportioning of the delay times T_1 and T_2 of the shift register elements. At given values of T_1 and T_2 the difference between the transfer functions $\tilde{H}_1(\omega)$ and $\tilde{H}_2(\omega)$ to be achieved and the functions in the considered expansion interval represented by the Fourier series $\tilde{H}_1(\omega)$ and $\tilde{H}_2(\omega)$ depend on the numbers $2n+1$ and $2m+1$ respectively of tappings used. For completeness' sake it is to be noted that an even number of tappings may alternatively be used. Mathematically, an odd number is still used but then all coefficients having an even index are set equal to zero.

The operation of the device of FIG. 1 for the case of amplitude modulation will now be described with reference to FIG. 12.

FIG. 12 shows at *a* the spectrum $F_1(\omega)$ of an information pulse provided by the information source 1. The transfer function $H_1(\omega)$ to be approximated is shown in *b* by which function the bandwidth of the information signal $f_1(t)$ is limited to ω_0 . The Fourier expansion of $H_1(\omega)$ results for $n=5$ in the transfer function shown in *c*. The periodicity $\omega_{p1}=2\pi/T_1$ is identically equal to the shift frequency $\omega_r=2\pi/T_1$ of the shift register 4 and in this case it is assumed to be equal to $\omega_r=2\omega_0$. For finite values of n (in the Example of FIG. 1: $n=5$) the function $\tilde{H}_1(\omega)$ shown in *d* is produced. Filtering of the function $f_1(t)$ with the transfer function $\tilde{H}_1(\omega)$ provides the product $F_{11}(\omega) = F_1(\omega) \tilde{H}_1(\omega)$ which product is shown in *e*. The spectrum of the series of rectangular carrier pulses produced by carrier pulse generator 15 is shown in *f*. If the ratio of pulse duration and pulse repetition interval is 1:2, only odd harmonics of the radial frequency ω_c are produced. To select the carrier radial frequency ω_c , the higher harmonics are filtered out with the aid of the transfer function $H_2(\omega)$ to be approximated, which is shown in *g*. $H_2(\omega)$ thus should be prescribed in such a manner that the value of $H_2(\omega)$ is equal to zero for $\omega=k\omega_c$ (k = integer) with the exception of $k = \pm 1$. The Fourier series $\tilde{H}_2(\omega)$ of periodicity $\omega_{p2}=2\pi/T_2$ which corresponds to the shift frequency $\omega_8=2\pi/\delta$ of shift register 17 is shown in *h*. Here, the value of 10 is chosen for the ratio ω_8/ω_c . The product $F_{22}(\omega) = F_2(\omega) \tilde{H}_2(\omega)$ is shown in *i*. The convolution operation according to Equation (22) provides the spectrum $\phi(\omega)$ of the amplitude-modulated signal shown in *j*. A complete suppression of the unwanted frequency components which are already greatly reduced is obtained with the aid of a bandpass filter connected to the output or with the aid of the transmission channel itself connected to the output. The resultant spectrum is shown in *k*.

The coefficients $C_{\nu\mu}$ are calculated in accordance with Equation (22). The coefficients C_{ν} are found from the Fourier expansion of the transfer function $H_1(\omega)$ according to *c* in FIG. 12:

$$C_{\nu} = \frac{1}{\omega_r} \int_{-\omega_r}^{\omega_r} \exp\left(j\nu \frac{2\pi}{\omega_r} \omega\right) d\omega = 2 \frac{\omega_0}{\omega_r} \sin\left(\nu 2\pi \frac{\omega_0}{\omega_r}\right) \quad (26)$$

If the coefficients C_{μ} are chosen in accordance with the prescription:

$$C_\mu = \begin{cases} 2 \frac{\omega_c}{\omega_\delta} \cdot \cos \left(\mu 2\pi \frac{\omega_c}{\omega_\delta} \right), & |\mu| < \frac{\omega_\delta}{2\omega_c} \\ \frac{\omega_c}{\omega_\delta} \cdot \cos \left(\mu 2\pi \frac{\omega_c}{\omega_\delta} \right), & |\mu| = \frac{\omega_\delta}{2\omega_c} \\ 0, & |\mu| > \frac{\omega_\delta}{2\omega_c} \end{cases} \quad (27)$$

with

$$\omega_\delta/2\omega_c = i, i = 1, 2, 3, \dots \quad (28)$$

then it can be shown after some calculation that the associated Fourier series:

$$\tilde{H}_2(\omega) = \sum_{\mu=-i}^i C_\mu \exp \left(-j\mu \frac{2\pi}{\omega_\delta} \omega \right) \quad (29)$$

for all values $\omega = k\omega_c$ ($k = \text{integer}$) is equal to zero with the exception of values $\omega = \pm(2ik \pm 1)\omega_c$ for which the function value is equal to 1. FIG. 12 shows at h the variation of $\tilde{H}_2(\omega)$ for the case when i is 5. The function value 1 then occurs at $\pm\omega_c, \pm 9\omega_c, \pm 11\omega_c, \pm 19\omega_c, \pm 21\omega_c$, etc.

Substitution of the Equations (26) and (27) in Equation (22) then immediately results in Equation (1).

Vestigial sideband signals and single sideband signals may alternatively be generated with the aid of the so-called phase method. The operation of the relevant device provided with two shift registers will be described with reference to the function diagrams shown in FIG. 11. Two function units of the shape shown in FIG. 10 are necessary for the device, which units consist of the networks 292, 293, 295 and 296 and the two modulators 294 and 297. The transfer functions $\tilde{H}_1(\omega)$ and $\tilde{H}_2(\omega)$ of the networks 292 and 293 are chosen as in the previous Example of the amplitude modulator. Apart from higher frequency components the modulator 294 constitutes in accordance with Equation (25) the product $f_{11}(t) \cdot \cos(\omega_c t)$, in which $f_{11}(t)$ is the information signal limited in bandwidth. The phase method requires a second signal $f_{12}(t) \cdot \sin(\omega_c t)$ to be generated in which $f_{12}(t)$ is the Hilbert-transform of the band-limited signal $f_{11}(t)$. Addition or subtraction of the two products in a combination device 298 produces the lower or upper sideband signals.

The network 296 is used for generating the carrier $\sin(\omega_c t)$ from the carrier pulse series $f_2(t)$ the transfer function of which network is equal to

$$\tilde{H}_4(\omega) = \sum_{\mu=-i}^i \gamma_\mu \exp \left(-j\mu \frac{2\pi}{\omega_\delta} \omega \right) \quad (30)$$

This transfer function $\tilde{H}_4(\omega)$ is distinguished from $\tilde{H}_2(\omega)$ in that $\tilde{H}_4(\omega)$ is an odd function of the frequency. Analogous to Equation (27) the associated coefficients are given by:

$$\gamma_\mu = \begin{cases} 2 \frac{\omega_c}{\omega_\delta} \cdot \sin \left(\mu 2\pi \frac{\omega_c}{\omega_\delta} \right), & |\mu| < \frac{\omega_\delta}{2\omega_c} \\ \frac{\omega_c}{\omega_\delta} \cdot \sin \left(\mu 2\pi \frac{\omega_c}{\omega_\delta} \right), & |\mu| = \frac{\omega_\delta}{2\omega_c} \\ 0, & |\mu| > \frac{\omega_\delta}{2\omega_c} \end{cases} \quad (31)$$

in which case also Equation (28) applies.

The Hilbert-transform $f_{12}(t)$ of the band-limited signal $f_{11}(t)$ is obtained with the network 295 whose transfer function $\tilde{H}_3(\omega)$ corresponds to $\tilde{H}_1(\omega)$ but with an odd continuation. It is known from network theory that odd transfer functions are purely imaginary, which property has the physical significance

70

that all frequency components are shifted 90° in phase. The coefficients γ_ν of the Fourier series $\tilde{H}_3(\omega)$ can then be calculated with the aid of

$$\gamma_\nu = \frac{1}{\omega_r} \int_{-\omega_r}^{\omega_r} j \text{sign}(\omega) \exp \left(j\nu \frac{2\pi}{\omega_r} \omega \right) d\omega = 2 \frac{\omega_\delta}{\omega_r} \text{ci} \left(\nu 2\pi \frac{\omega_\delta}{\omega_r} \right) \quad (32)$$

10

In this equation the function $ci(x)$ is an abbreviated notation of the function $(1 - \cos x)/x$.

For the practical realization it is possible to use two devices in accordance with FIG. 1, to provide both matrix networks with coefficients $C_\nu C_\mu$ and $\gamma_\nu \gamma_\mu$ and to add or subtract the signals generated. A considerably simpler device is, however, obtained when connecting both matrix networks to the same shift register and when adding or subtracting the relevant coefficients in conformity with Equation (17):

$$C_{\nu\mu} = C_\nu C_\mu \pm \gamma_\nu \gamma_\mu \quad (33)$$

25 Substitution of the Equations (26), (27), (31) and (32) in Equation (33) then results in Equation (4). Since an infinitely steep cut-off at the frequency $\omega = \omega_\delta$ can be obtained with a finite number of coefficients, a vestigial sideband signal is produced.

30 In the structure of the device shown in FIG. 5 more favorable transfer functions $H_1(\omega)$ and $H_2(\omega)$ may be used. These are graphically shown in FIG. 13. The relevant Fourier coefficients are:

$$C_\nu = \frac{2}{\pi} \frac{\omega_\delta}{\omega_r} \cdot \frac{1 + \cos \left(\nu 2\pi \frac{\omega_\delta}{\omega_r} \right)}{1 - \left(2\nu \frac{\omega_\delta}{\omega_r} \right)^2} \quad (34)$$

$$\gamma_\nu = \frac{2}{\pi} \frac{\omega_\delta}{\omega_r} \cdot \frac{\sin \left(\nu 2\pi \frac{\omega_\delta}{\omega_r} \right)}{1 - \left(2\nu \frac{\omega_\delta}{\omega_r} \right)^2} \quad (35)$$

35 It is apparent from the Equations (34) and (35) that these coefficients converge more quickly than the coefficients in the Equations (26) and (32) and that consequently a single sideband signal is produced. The carrier generation is effected in the same manner as in the vestigial sideband system described; Equation (5) then follows from the Equations (27), (31), (34) and (35).

40 As already stated a carrier signal with binary phase modulation may be considered to be an amplitude-modulated signal having a suppressed carrier. If the series of binary information pulses is denoted by $f_1(t)$ likewise as in the foregoing, then the relation for the amplitude-modulated signal applies:

$$F(t) = f_1(t) \cos \omega_c t \quad (36)$$

45 If the information pulses have the normalized amplitude values of 0 or 1, the phase-modulated signal can be written as follows:

$$F(t) = f_1(t) \cos \omega_c t - \frac{1}{2} \cos \omega_c t = [f_1(t) - \frac{1}{2}] \cos \omega_c t \quad (37)$$

50 The expression: $[f_1(t) - \frac{1}{2}]$ indeed only assumes the values $\pm\frac{1}{2}$ and $-\frac{1}{2}$ and thus produces a phase modulation of the carrier between 0° and 180°.

55 FIG. 6 shows the relevant device. Without the additional attenuation networks 274-284 an amplitude-modulated signal appears at the output 272 if the coefficients $C_{\nu\mu}$ of the matrix network 28 are chosen in conformity with Equation (1). The additional attenuation networks only cause the output signal to be reduced in conformity with Equation (37) by the carrier $\frac{1}{2} \cos(\omega_c t)$. It follows immediately from Equation (27) that the coefficients are to be proportioned for this purpose in conformity with Equation (6).

As already stated hereinbefore, the device according to FIG. 1 may alternatively serve for generating a phase-modulated signal if, instead of a multiplicative combination with the aid of AND-gates, in the modulation elements 30-150 a modulo-2-addition with the aid of exclusive OR-gates is effected. Equation (15) is then to be modified as follows:

$$F(t) = \int_{-\infty}^{\infty} \int_{-\infty}^{\infty} h_1(\tau_1) h_2(\tau_2) f_1(t - \tau_1) + f_2(t - \tau_2) d\tau_1 d\tau_2 \quad (38)$$

Since in this case the functions $f_1(t)$ and $F_2(t)$ can only assume the values 0 and 1, the modulo-2-addition in accordance with the following truth table:

f_1	f_2	$f_1 \oplus f_2$	$(f_1 - f_2)^2$
0	0	0	0
1	0	1	1
0	1	1	1
1	1	0	0

may be replaced as follows:

$$F(t) = \int_{-\infty}^{\infty} \int_{-\infty}^{\infty} h_1(\tau_1) h_2(\tau_2) [f_1(t - \tau_1) - f_2(t - \tau_2)]^2 d\tau_1 d\tau_2 \quad (39)$$

Elaboration of Equation (39) while taking into account the equations:

$$\begin{aligned} f_1^2(t - \tau_1) &= f_1(t - \tau_1); f_1(t - \tau_1) = 0,1 \\ f_2^2(t - \tau_2) &= f_2(t - \tau_2); f_2(t - \tau_2) = 0,1 \end{aligned} \quad (40)$$

leads to the following result:

$$\begin{aligned} F(t) &= \int_{-\infty}^{\infty} h_2(\tau_2) d\tau_2 \int_{-\infty}^{\infty} h_1(\tau_1) f_1(t - \tau_1) d\tau_1 \\ &- 2 \int_{-\infty}^{\infty} \int_{-\infty}^{\infty} h_1(\tau_1) h_2(\tau_2) f_1(t - \tau_1) f_2(t - \tau_2) d\tau_1 d\tau_2 \\ &+ \int_{-\infty}^{\infty} h_1(\tau_1) d\tau_1 \int_{-\infty}^{\infty} h_2(\tau_2) f_2(t - \tau_2) d\tau_2 \end{aligned} \quad (41)$$

With the pulse response of the ideal lowpass filter:

$$h_1(\tau_1) = \frac{1}{\pi} \cdot \frac{\sin \omega_0 \tau_1}{\tau_1} \quad (42)$$

and the pulse response of the ideal carrier filter:

$$h_2(\tau_2) = \begin{cases} \frac{\omega_c}{\pi} \cos \omega_c \tau_2, & |\tau_2| < \frac{\pi}{\omega_c} \\ 0, & |\tau_2| > \frac{\pi}{\omega_c} \end{cases} \quad (43)$$

the following relation may be derived from Equation (41):

$$\begin{aligned} F(t) &= -2 \int_{-\infty}^{\infty} \int_{-\infty}^{\infty} h_1(\tau_1) h_2(\tau_2) f_1(t - \tau_1) f_2(t - \tau_2) d\tau_1 d\tau_2 \\ &+ \int_{-\infty}^{\infty} h_2(\tau_2) f_2(t - \tau_2) d\tau_2 \end{aligned} \quad (44)$$

Apart from a constant factor $-\frac{1}{2}$ which is not important, Equation (44) describes the generation of a phase-modulated signal with the aid of the device shown in FIG. 6. This proves that the devices according to FIG. 6 and FIG. 1 are equivalent if in the latter the multiplicative combination is replaced by modulo-2-addition.

A frequency-modulated signal may be generated with the device according to FIG. 7. The operation will be described with reference to the function diagram shown in FIG. 14. The transfer functions of the networks 292, 293, 295 and 296 are chosen likewise as in the vestigial sideband system already described, that is to say, $\tilde{H}_1(\omega)$ approximates the characteristic of the ideal lowpass filter of radial cut-off frequency ω_0 and $\tilde{H}_2(\omega)$ approximates the characteristic of the ideal low-

pass filter of the same radial cut-off frequency which brings about an additional phase shift of 90° . $H_2(\omega)$ and $H_4(\omega)$ are the transfer functions of the previously described carrier filters which derive the carriers $\cos(\omega_c t)$ and $\sin(\omega_c t)$ from the series of carrier pulses from the carrier pulse generator 15.

The signal shown at c in FIG. 8 appears at the output of the OR-gate 285. If the information signal shown at a in FIG. 8 corresponds to the logic value 1, the carrier signal $\cos(\omega_c t)$ appears at the output of the modulator 294. The same carrier signal of half the amplitude of the output signal of the modulator 294 is subtracted in the combination device 298 (inverter 299). The modulator 297 does not provide a contribution since the filter network 295 does not pass direct current. Thus the signal $\frac{1}{2} \cos(\omega_c t)$ occurs at the output 272.

If the information signal shown at a in FIG. 8 corresponds to the logic value 0, the network 292 produces the signal $\frac{1}{2} [1 + \cos(\omega_0 t)]$ if the transfer function $H_1(\omega)$ for $\omega = \omega_0$ assumes the value $\pi/4$. The amplitude-modulated signal is produced at the output of the modulator 294: $F_1(t) = \frac{1}{2} \cos \omega_0 t + \frac{1}{2} [\cos(\omega_0 t + \omega_0 t) - \cos(\omega_0 t - \omega_0 t)]$ (45)

The network 295 accordingly provides the signal $\frac{1}{2} \sin(\omega_0 t)$; the direct current component is suppressed again. The following signal is then produced at the output of the modulator 297:

$$F_2(t) = \frac{1}{2} [\cos(\omega_0 t + \omega_0 t) - \cos(\omega_0 t - \omega_0 t)] \quad (46)$$

The inverter 299 still supplies the carrier signal $-\frac{1}{2} \cos(\omega_0 t)$. Addition of all three signals in the combination device 298 then results in the relation:

$$F_1(t) + F_2(t) - \frac{1}{2} \cos(\omega_0 t) = \frac{1}{2} \cos(\omega_0 t - \omega_0 t) \quad (47)$$

The frequency thus assumes the values ω_0 and $\omega_0 - \omega_0$. If the transfer function $H_3(\omega)$ is provided with a negative sign, the result is a frequency variation between ω_0 and $\omega_0 + \omega_0$.

The subtraction of the carrier signal $\frac{1}{2} \cos(\omega_0 t)$ may again be effected with additional attenuation networks or by modulo-2-addition in the modulation elements. The last-mentioned version underlies the device of FIG. 7.

The operation of the orthogonal modulator according to FIG. 9 can be explained in a simple manner. In principle two independent devices of the shape shown in FIG. 1 are used. Only the carrier generation with the aid of the shift register 17 $\cos(\omega_c t)$ is effected in the first system and modulation with $\sin(\omega_c t)$ is effected in the second system. This property of the coefficients is directly apparent from the Equations (1) and (10).

The mathematical considerations given so far may be extended to devices including 3 shift registers or even to devices including N-shift registers. FIG. 15 shows the function diagram of the basic element of a device having q shift registers. The functions $f_1(t), f_2(t), \dots, f_{q-1}(t)$ and $f_q(t)$ are applied to the inputs of the linear, passive, time-invariant networks with pulse responses $h_1(t), h_2(t), \dots, h_{q-1}(t)$ and $h_q(t)$. The output signals of the networks are combined in the modulator 294 in accordance with a given mathematical interrelationship and produce the signal $F(t)$.

In the case of a multiplicative combination in the modulator 294 the following relation analogous to Equation (15) may be set up for the device according to FIG. 15:

$$\begin{aligned} F(t) &= \int_{-\infty}^{\infty} \int_{-\infty}^{\infty} \dots \int_{-\infty}^{\infty} h_1(\tau_1) h_2(\tau_2) \dots \\ &f_q(\tau_q) f_1(t - \tau_1) f_2(t - \tau_2) \dots f_q(t - \tau_q) d\tau_1 d\tau_2 \dots d\tau_q \end{aligned} \quad (48)$$

This formula may alternatively be written in a more general form if several of the basic elements shown in FIG. 15 are connected in parallel in a manner corresponding to FIG. 11. Equation (48) then is:

$$\begin{aligned} F(t) &= \int_{-\infty}^{\infty} \int_{-\infty}^{\infty} \dots \int_{-\infty}^{\infty} h(\tau_1, \tau_2, \dots, \tau_q) f_1(t - \tau_1) f_2(t - \tau_2) \dots \\ &\dots f_q(t - \tau_q) d\tau_1 d\tau_2 \dots d\tau_q \end{aligned} \quad (49)$$

In accordance with Equation (17) there applies that:

$$\begin{aligned} h(\tau_1, \dots, \tau_q) &= h_1(\tau_1)h_2(\tau_2) \dots h_q(\tau_q) \\ &+ h_{q+1}(\tau_1)h_{q+2}(\tau_2) \dots h_{2q}(\tau_q) \\ &+ h_{2q+1}(\tau_1)h_{2q+2}(\tau_2) \dots h_{3q}(\tau_q) + \dots \end{aligned} \quad (50)$$

If again the integration is replaced by an addition, then there follows that:

$$F(t) = \sum_{\nu=-n}^n \sum_{\mu=-m}^m \dots \sum_{\lambda=-l}^l T_1 T_2 \dots T_q h(\nu T_1, \mu T_2, \dots, \lambda T_q) \quad (51)$$

Then the N-dimensional coefficients are produced:

$$C_{\nu\mu\dots\lambda} = T_1 T_2 \dots T_q h(\nu T_1, \mu T_2, \dots, \lambda T_q) \quad (52)$$

of which the "dimension" N is equal to q.

For the practical realization of the device shown in FIG. 15 q shift registers whose shift register elements are branched are required, as follows from the structure of the Equations (51) and (52). Each signal thus branched is multiplied by all signals derived from the other shift registers. The resultant signal is provided with a weighting factor corresponding to the value associated with the coefficients of Equation (52). The partial signals weighted in this manner are finally added so as to obtain the desired signal F(t).

Of special technical importance is the cascade arrangement of two devices which are provided with two shift registers each. FIG. 16 shows the relevant function diagram. The following relation between the output function F(t) and the input functions f₁(t) and f₂(t) and f₄(t) is found with the aid of Equation (15)

$$\begin{aligned} F(t) &= \int_{-\infty}^{\infty} \int_{-\infty}^{\infty} \int_{-\infty}^{\infty} \int_{-\infty}^{\infty} h_1(\tau_1)h_2(\tau_2)h_3(\tau_3)h_4(\tau_4)f_1(t-\tau_1) \\ &- \tau_1)f_2(t-\tau_3-\tau_2)f_4(t-\tau_4) d\tau_1 d\tau_2 d\tau_3 d\tau_4 \end{aligned} \quad (53)$$

In this case it is assumed that pure multiplication takes place in the modulators 294 and 297.

It follows from Equation (52) for the coefficients that:

$$C_{\nu\mu\lambda} = T_1 T_2 T_3 T_4 h(\nu T_1, \mu T_2, \lambda T_3, \lambda T_4) \quad (54)$$

The representation of the series thus is:

$$\begin{aligned} F(t) &= \sum_{\nu=-n}^n \sum_{\mu=-m}^m \sum_{\lambda=-k}^k \sum_{\lambda=-l}^l C_{\nu\mu\lambda} f_1(t-\lambda T_3) \\ &- \nu T_1) f_2(t-\lambda T_3 - \mu T_2) f_4(t - \lambda T_4) \end{aligned} \quad (55)$$

This expression shows that one shift register is economized and hence three shift registers may sufficient if it is only ensured that the ratios of the shift periods T₁/T₂ and T₃/T₄ are rational. The shift register for generating the function f₄(t) must be tapped at equidistant time distances. The principle of generating the function f₁(t-T₃-T₁) is apparent from FIG. 17. The signal f₁(t) is applied to the shift register which for the sake of clarification in the figure is shown as an ideal delay line 300. The fictitious zero point on the time axis is again chosen to be in the center of the delay line 300. For the case $\nu = -1$, tappings are to be distinguished for $\phi = 0, \pm 1, \pm 2$, and ± 3 . The signal f₁(t-2T₃+T₁) can then be derived, for example, at $\nu = 1$ and $\phi = 2$.

Correspondingly, the signal f₂(t- $\phi T_3 - \mu T_2$) can be generated with a following shift register. To generate the signals f₁(t- $\phi T_3 - \nu T_1$) and f₂(t- $\phi T_3 - \mu T_2$) it is assumed that the ratios T₁/T₃ and T₂/T₃ are rational since only at these points a signal can be tapped which are spaced apart over a time distance of one shift period or an integral multiple thereof.

Each signal thus tapped from a shift register is multiplied by all signals which are derived from the two other shift registers. The resultant products are provided with a weighting factor corresponding to the coefficients of Equation (54) and are

subsequently added. The signals f₁(t), f₂(t) and f₄(t) may be formed by rectangular synchronous pulses, but alternatively analog signals f₁(t), f₂(t) and f₄(t) may be handled if these signals, prior to handling, undergo an analog-to-digital conversion.

FIG. 18 shows the function diagram for a device for the transmission of synchronous information pulses by means of single sideband modulation in accordance with the method described in patent application Ser. No. 786,111, filed Dec. 23, 1968 now U.S. Pat. No. 3,588,702. As is apparent from FIG. 18, this function diagram shows the parallel arrangement of two cascade circuits as are shown in FIG. 16. The series of information pulses f₁(t) whose radial clock frequency is ω_r is applied to the networks 292 whose characteristic corresponds

10 to the curve a of FIG. 13 in which $\omega_r = \omega_r/2$. The series of rectangular carrier pulses f₃(t) having a radial clock frequency of $\omega_r/2$ applies to the outputs of the networks 293 and 296 an orthogonal pair of subcarriers at a radial frequency of $\omega_r/4$. The signals produced after the modulators 294 and 297 are filtered by the lowpass filters 295 whose cut-off frequency $\omega_c = \omega_r/4$ and are subsequently subjected to a further orthogonal modulation in modulators 382 and 383. The carriers of radial frequency ω_c required for this purpose are obtained from the carrier pulse series f₄(t) with the aid of the networks 380 and 381. The sum or the difference at the output of the unit provides the desired signal sideband signal F(t).

For the practical realization of the transmission device whose function diagram is shown in FIG. 18 three shift registers are sufficient, if the conditions for the cascade circuit of FIG. 16 relative to the ratios T₁/T₃ and T₂/T₃ are also satisfied because in this device as well as in the cascade circuit of FIG. 16 only three functions are applied externally.

FIG. 19 shows a practical embodiment of this single sideband modulation device in which the elements corresponding to those in the device of FIG. 5 have the same reference numerals. The information source 1 passes the series of information pulses f₁(t) through the code converter 273 to the shift register 4 which consists of, for example, 38 shift register elements 301 - 338. A subcarrier pulse generator 339 generates the series of rectangular subcarrier pulses f₃(t) which is applied to a shift register 341 which is constituted, for example, by 36 shift register elements 342-377 whose shift frequency f₃ is generated with the aid of a multiplier 340. The series of carrier pulses f₄(t) is generated by a carrier pulse generator 15. For convenience's sake the matrix network 28 is not further shown, but FIG. 19 shows only one modulation element 378 which effects a multiplicative combination of the input signals, the resultant logical product being weighted with the aid of the attenuation networks 379 and 29. The associated transfer coefficient has the shape of C_{μλ} in which ν indicates a shift register element of shift register 4, μ indicates an element of shift register 341, λ indicates an element of shift register 4 and 341 with reference to the elements ν and μ (compare FIG. 17). In the given case the transfer coefficient of modulation element 378 is given by $\nu = 3, \mu = 0, \lambda = -1$ and $\lambda = 1$ and is then C₃₀₋₁₁.

60 The formation of the transfer coefficients is apparent from the function diagram shown in FIG. 18. The Fourier expansion of a characteristic according to a in FIG. 13 showing the networks 292 leads to the coefficients γ_v of Equation (35) with $\omega_r = \omega_r/2$ and $\omega_c = 2\pi/T_1$. Likewise the Fourier expansion of the lowpass filter characteristic of the networks 295 at a cutoff radial frequency $\omega_r/4$ provides the coefficients C_λ in accordance with Equation (26) with $\omega_r = \omega_r/4$ and $\omega_c = 2\pi/T_2$. The Fourier development of the transfer functions of the subcarrier filters 293 and 296 leads to the coefficients C_μ in accordance with Equation (27) and to γ_λ in accordance with Equation (31) with the values $\omega_r = \omega_r/4$ and $\omega_c = 2\pi/T_3$ applying to both of them. Likewise the Fourier expansions of the transfer functions of the carrier filters 380 and 381 provide the coefficients C_λ in accordance with Equation (27) and γ_λ in accordance with Equation (31) with the value $\omega_r = 2\pi/T_4$ applying to both of them. For a maximum suppression of the

70 75

subcarrier and carrier harmonics Equation (28) must also be satisfied in this case.

The transfer coefficients $C_{\nu\mu\kappa\lambda}$ are now found from the equation:

$$C_{\nu\mu\kappa\lambda} = \gamma_\nu C_\kappa (C_\nu C_\kappa \pm \gamma_\mu \gamma_\lambda) \quad (56)$$

The single sideband signal occurring at the output 272 has a bandwidth $\omega_r/2$, while the carrier frequency ω_c is located in the center of the frequency band of the single sideband signal.

The proportioning of the transmission device of FIG. 19 for a transmission speed of 1,200 Baud and a frequency band of 10 from 300 to 3,300 Hz to be used is as follows: Clock frequency of the clock pulse generator 2:

$$f_r = 1/T = 1,200 \text{ Hz}$$

Shift frequency of the shift register 4:

$$f_r = 1/T_1 = 2f_r = 2,400 \text{ Hz.}$$

Shift frequency of shift register 341:

$$f_{\delta H} = 1/T_2 = 2f_r = 2,400 \text{ Hz.}$$

Reciprocal value of the delay time T_3 :

$$1/T_3 = f_{T_3} = 1,200 \text{ Hz.}$$

Carrier frequency (center of the frequency band of the single sideband signal):

$$f_c = 1,800 \text{ Hz.}$$

Shift frequency of shift register 17:

$$f_6 = 1/T_4 = 18 \text{ kHz.}$$

The device according to the invention is also suitable for obtaining N-path filters. FIG. 20 shows the known block diagram of an N-path filter ($N = 3$). FIG. 20 shows that the same network 295 is incorporated in each path, each of these three networks being preceded by switches 387, 388, 389 and followed by a second group of switches 390, 391 and 392. The switches are directly driven by means of a series of rectangular carrier pulses in the first path, and in the second and third paths through the networks 385 and 386 which ensure phase shifts of 120° and 240°, respectively.

In accordance with the teaching of the invention the N-path filter illustrated in FIG. 20 may be represented by a function diagram as is shown in FIG. 21.

Each path is provided with a cascade circuit of the shape shown in FIG. 16. The networks 295 are the elements which essentially determine the frequency variation. The networks 292 ensure a limitation of the frequency band of the information signal $f_1(t)$. The networks 293, 296 and 393 generate the carrier from a uniform rectangular pulse series $f_2(t)$, a phase shift of 0° being obtained in the first path, a phase shift of 120° being obtained in the second path and a phase shift of 240° being obtained in the third path.

The switches 387, 388, 389, 390, 391 and 392 in FIG. 20 are replaced by the purely multiplicatively functioning modulators 394, 395, 396, 397, 398 and 399.

Starting from Equation (55) and taking into account that $f_1(t)$ and $f_2(t)$ are identical, the following relationship is obtained between the output signal and the input signals $f_1(t)$ and $f_2(t)$:

$$F(t) = \sum_{\nu=-n}^n \sum_{\mu=-m}^m \sum_{\kappa=-k}^k \sum_{\lambda=-l}^l C_{\nu\mu\kappa\lambda} f_1(t - \kappa T_3 - \nu T_1) f_2(t - \mu T_3 - \lambda T_4) \quad (57)$$

For the practical embodiment of an N-path filter of which a function diagram is shown in FIG. 21, two shift registers are sufficient if the given conditions for the cascade circuit according to FIG. 16 relative to the ratios T_1/T_3 and T_2/T_4 are satisfied and if also the ratio T_2/T_4 is rational, since in this case only two functions are to be applied externally.

FIG. 22 shows the practical embodiment of this N-path filter in which the elements have the same reference numerals as those in the device of FIG. 19. The information source 1 applies the series of information pulses $f_1(t)$ to be filtered to the shift register 4, which consists of, for example, 56 shift register elements 400-455. A subcarrier pulse generator 339 generates the series of rectangular subcarrier pulses $f_2(t)$ which is applied to a shift register 341 which consists of, for example, 28 shift register elements 342-369. For convenien-

ce's sake the matrix network 28 is not shown, but only one modulation element 456 is shown in FIG. 22, which modulation element 456 brings about a multiplicative combination of the input signals, the resultant logical product being weighted with the aid of the attenuation networks 457 and 29. The associated transfer coefficient has the shape $C_{\nu\mu\kappa\lambda}$ in which ν indicates a shift register element of shift register 4, μ and λ indicate elements of shift register 341 and ϕ indicates the tapping on the shift registers 4 and 341 with reference to the elements ν , μ and λ reckoned from the center of the shift registers 4 and 341 (compare FIG. 17). The transfer coefficient of the modulation element 456 is given as an example by $\nu = -1$, $\mu = 0$, $\lambda = 2$, $\phi = -1$ and thus is C_{-102-1} .

The formation of the transfer coefficients $C_{\nu\mu\phi\lambda}$ of the weighting devices of the N-path filter having three paths can be derived mathematically with reference to the function diagram given in FIG. 21 for the embodiments given so far. The Fourier expansions of the transfer functions of the subcarrier filters 293, 296 and 393, which provide the subcarrier with the phases 0°, 120° and 240° produce coefficients which appear as fitting linear combinations of the coefficients C_μ and γ_ν calculated from Equations (27) and (31). To obtain maximum suppression of unwanted modulation products particularly Equation (28) must be satisfied.

For the practical situation where, for example, the band of from 225 - 375 Hz must be filtered from the frequency spectrum of a series of information pulses having a clock frequency $f_r = 1,200 \text{ Hz}$, a few specific values follow hereinafter:

Subcarrier frequency:

$$f_c = 300 \text{ Hz.}$$

Shift frequency of shift register 4:

$$f_r = 1/T_1 = 2,400 \text{ Hz.}$$

Shift frequency of shift register 341:

$$f_\delta = 1/T_2 = 1/T_4 = 1,200 \text{ Hz.}$$

Reciprocal value of the delay period T_3 :

$$1/T_3 = 1,200 \text{ Hz.}$$

As FIG. 22 shows only two shift registers are required for the functions $f_1(t)$ and $f_2(t)$. This produces the interesting configuration of two separate signals derived from one shift register being applied to one and the same modulation element.

In addition it is possible to derive different output signals in the matrix network from one and the same modulation element for certain uses. Thus, for example, when using the device according to the invention for generating a carrier frequency raster, the output circuit of each modulation element is connected through different weighting devices to different combination devices each of which provide a frequency $f_c \pm n f_r$ while the information source provides a periodical series of rectangular pulses having a pulse repetition frequency of f_r to the modulation elements.

FIG. 23 shows a practical embodiment of such a device for generating a carrier frequency raster. In this device the information source 501 supplies binary pulses at a clock frequency f_r of, for example, 50 Hz. These binary pulses are applied to a shift register 502 which is provided with a plurality of shift register elements 503, 504, 505, 506, 507, 508, 509 and 510.

The shift frequency f_r of the shift register 502 is an integral multiple of the clock frequency f_r and is generated with the aid of a multiplier 511. The shift frequency f_r is, for example, 10 times higher than the clock frequency f_r and amounts to 500 Hz.

The carrier oscillator in the form of a carrier pulse generator 512 supplies a series of equidistant carrier pulses which are applied to a shift register 513 having a plurality of shift register elements 514, 515, 516, 517, 518, 519, 520 and 521. The carrier pulse frequency f_c is, for example, 1,000 Hz. The shift frequency f_δ of the shift register 513 is an integral multiple of the carrier frequency f_c of the carrier pulse generator 512 and is also generated by means of a multiplier 522. The shift frequency f_δ is, for example, 10 times higher than the carrier frequency f_c and amounts to 10 kHz.

The output circuits of the shift register elements of the two shift registers 502 and 513 are connected to a matrix network

523. In this matrix network the nodes of the output circuits of the shift register elements of both shift registers 502 and 513 incorporate the modulation elements 524-548 which establish a logical combination of the stored binary pulses. The output signals of the modulation elements 524-548 are weighted with the aid of weighting networks constituted by attenuation networks 549-573 and combination device 574. The sum of the weighted output signals of the modulation elements 524-548 then occurs at the output 575 of the combination device 574.

As already extensively described hereinbefore, the signal from information source 501 is modulated on the carrier frequency f_c when suitably proportioning the weighting networks while unwanted modulation products are suppressed to a great extent. The method of modulation, for example, amplitude modulation, phase modulation or single sideband modulation is dependent on the choice of the transfer coefficients C_{rp} of the weighting networks.

The structure of the device described above is particularly simple when the information source 501 provides a periodical series of rectangular pulses of frequency f_T and when a frequency raster $f_c \pm nf_T$ must be generated. This frequency raster is shown in FIG. 24.

For generating this frequency raster the output circuits of each modulation element 524-548 are connected through different weighting devices to different combination devices each providing a frequency $f_c \pm nf_T$. FIG. 23 only shows a single additional weighting device and the associated combination device in which corresponding elements have the same reference numerals, but are provided with indices; of course further weighting devices and associated combination devices may be connected to the modulation elements 524-548 as is diagrammatically shown by the broken line near the modulation elements in FIG. 23. The transfer coefficients must then be proportioned in accordance with the equation below:

$$C_{rp} = \begin{cases} \frac{4n\omega_T}{\omega_r \omega_\delta} \cdot \cos \left[\nu 2\pi \frac{n\omega_T}{\omega_r} \pm \mu 2\pi \frac{\omega_c}{\omega_\delta} \right], & |\nu| < \frac{\omega_r}{2n\omega_T}, |\mu| < \frac{\omega_\delta}{2\omega_c} \\ 2 \frac{n\omega_T}{\omega_r \omega_h} \cdot \cos \left[\nu 2\pi \frac{n\omega_T}{\omega_r} \pm \mu 2\pi \frac{\omega_c}{\omega_h} \right], & \begin{cases} |\nu| < \frac{\omega_r}{2n\omega_T}, |\mu| = \frac{\omega_\delta}{2\omega_c} \\ |\nu| = \frac{\omega_r}{2n\omega_T}, |\mu| < \frac{\omega_\delta}{2\omega_h} \end{cases} \\ \frac{n\omega_T}{\omega_r \omega_\delta} \cdot \cos \left[\nu 2\pi \frac{n\omega_T}{\omega_r} \pm \mu 2\pi \frac{\omega_c}{\omega_\delta} \right], & |\nu| = \frac{\omega_r}{2n\omega_T}, |\mu| = \frac{\omega_\delta}{2\omega_c} \\ 0, & |\nu| > \frac{\omega_r}{2n\omega_T}, |\mu| > \frac{\omega_\delta}{2\omega_c} \end{cases} \quad (58)$$

$$\nu = 0, \pm 1, \pm 2, \dots$$

$$\mu = 0, \pm 1, \pm 2, \dots$$

$$\omega_T = 2\pi f_T, \omega_c = 2\pi f_c, \omega_r = 2\pi f_r, \omega_\delta = 2\pi f_\delta$$

In this manner it is achieved that the frequency raster $f_c \pm nf_T$ is generated with the aid of only one shift register for the carrier signal source 512 and only one shift register for the information signal source 501 as well as with the aid of only one matrix network 523. In that case the output voltages of the different combination devices 574, 574' do not influence each other because the reactive effects of the different combination devices through the weighting devices 549-573, 549'-573' to the common modulation elements 524-548 become negligibly small if it is ensured that the output resistance of the modulation elements 524-548 is maintained sufficiently small.

In addition to a pair of weighting devices for generating the frequency raster $f_c \pm nf_T$ a second pair of weighting devices may be connected to the same modulation elements, which second pair provides a second frequency raster $f_c \pm nf_T$ which relative to the original frequency raster has an arbitrary but

fixed phase shift of, for example, 90°. In addition, the device shown has the advantageous property that the frequencies f_c and f_T can be adjusted independently of each other, that is to say, f_c may be adjusted to, for example, 500 Hz and f_T may be adjusted to, for example, 10 Hz without it being necessary to change the device.

A considerable economy in the number of modulation elements is obtained in that only every other element of the shift registers 502, 513 is to be connected to modulation elements 524-548 in the matrix network 523. When pulses are applied to the shift registers 502-513 whose duration is equal to half the pulse repetition period and when there is a ratio between the shift frequency and the double pulse repetition frequency which ratio is given by $(2m+1) : 1$ with $m = 2, 3, 4, 5, \dots$ In the given embodiment this ratio is 5:1. Thus this step means that the number of nodes of the matrix network 523 and hence the number of modulation elements is reduced by a factor of 4. Thus, in the given embodiment only 25 modulation elements are required.

In spite of this considerable economy in the number of modulation elements it has been found that this does not detract from the suppression of the unwanted modulation products which both in practice and strictly mathematically may be represented in the manner already extensively described hereinbefore.

The devices according to the invention differ from the known devices not only by their advantages already mentioned, namely the structure suitable for integration in a semiconductor body, the great suppression of unwanted modulation products as well as the general possibilities of use, but also by a very essential advantage which is illustrated by the embodiments shown in FIGS. 16-24. As is apparent from these complicated modulation systems, shift registers and/or modulation elements may be utilized simultaneously and several times. Particularly a shift register may be connected to

60 the modulation elements of various matrix networks or multiple modulation may be obtained by connecting more than two shift register elements of a shift register to the input circuit of the modulation elements, or the output circuit of the modulation elements may be connected through different weighting devices to different combination devices. In complicated modulation systems it is achieved in this manner that an essential economy in the number of modulation elements and shift registers is obtained which leads to new methods of structure in full conformity with the teaching according to the invention 65 extensively described with reference to the embodiments. It is this property that gives the device according to the invention considerable advantages upon carrying complicated modulation systems into effect.

Under certain circumstances an essential economy in the 70 number of shift register elements may be achieved if at least

one of the used shift registers is formed by a cascade circuit of partial shift registers whose shift frequencies have different values. As has been found from extensive experiments a high shift frequency is to be chosen for the partial shift register whose weight coefficients corresponding to the constituting values of the pulse response show great difference. To limit the number of apparatus required for generating the different shift frequencies, it is advantageous that these shift frequencies mutually differ by a factor of 2^i ($i=1, 2, 3, \dots$).

A further simplification of the shift registers for the carrier pulses is effected by having half a cycle of the periodical series of pulses circulate in accordance with the principle of a ring counter in a shift register whose shift register elements also have a complementary output. In the device according to FIG. 1, for example, only five instead of 10 shift registers are then required. The matrix network of the modulation elements and the weighting networks remain, however, unchanged.

As has been illustrated in the previous embodiments with reference to a few examples, there are different possibilities and simplifications of the devices according to the invention, but in addition there are more embodiments possible. For example, instead of attenuation networks it is alternatively possible to use amplifiers having a suitably chosen amplification factor for the weighting devices. Furthermore, the starting point for the control of the shift registers may be a single common pulse generator from which the clock frequency for the information pulses or the carrier frequency may be derived with the aid of frequency dividers.

The device according to the invention may be used advantageously in all systems in which modulation and filtering processes must be carried out. The device according to the invention may alternatively be used, for example, for generating the second or higher powers of filtered functions in which in this case the information source also operates as a carrier oscillator. Since the information source and carrier oscillator coincide in this case, only one shift register is required for this application, while different shift register elements of said shift register are connected to one and the same modulation element.

The device according to the invention may be used both at the transmitter end and at the receiver end, while the received signal at the receiver end must first be applied to an analog-to-digital converter. Transmitter, as well as analog-to-digital converter and receiver may be completely integrated in a semiconductor body.

In all these embodiments there always applies that both the information signals and the carrier oscillations are shifted in a shift register in a rhythm determined by a control generator and that the shift register elements in which the information signals and carrier oscillations are shifted are connected to the input circuits of the modulation elements incorporated in the nodes of a matrix network, the output signals of said modulation elements being applied through weighting devices to a common combination device.

What is claimed is:

1. A device for the transmission of information signals, said device comprising an information source, a first control generator, a first shift register coupled to said information source and having a plurality of shift register elements whose contents are shifted by said control generator, a second control generator, a carrier generator, a second shift register coupled to said second control generator and having a plurality of shift register elements whose contents are shifted by said second control generator, means connecting the carrier generator to the input means of said second shift register a matrix network having columns and rows which have nodes comprising modulation elements, means to couple said columns of said modulation elements respectively to the shift register elements of said first shift register, means to couple said rows of said modulation elements respectively to the shift register elements of said second shift register, a plurality of weighing devices coupled to said modulation elements, and a combination device for providing an output signal coupled to said weighing devices.

5 2. A device as claimed in claim 1, further comprising a clock pulse generator, said information source providing information pulses at instants of clock pulses from said clock pulse generator and means to couple said first control generator to said clock pulse generator.

3. A device as claimed in claim 1, wherein said second control generator is coupled to said carrier generator.

4. A device as claimed in claim 2, wherein the ratio of the repetition frequencies of said carrier generator and said 10 second control generator is equal to an integer.

5 5. A device as claimed in claim 1, wherein at least one of the shift registers comprises a cascade circuit of partial shift register whose shift frequencies have different values.

6. A device as claimed in claim 5, wherein the ratio of the 15 shift frequencies of the partial shift registers is equal to 2^i , where i is an integer.

7. A device as claimed in claim 1, wherein said second shift register comprises a ring counter.

8. A device as claimed in claim 1, wherein said shift register elements have two complementary output means.

9. A device as claimed in claim 1, wherein the weighting devices connected to the output circuits of the modulation elements in the matrix and the combination device comprise by an attenuation network.

25 10. A device as claimed in claim 1, wherein the modulation elements in the nodes of the matrix network comprise logic selection gates.

11. A device as claimed in claim 1, wherein the modulation 30 elements are provided with two complementary output means.

12. A device as claimed in claim 1, adapted for the transmission of analog signals, wherein a sampler is incorporated between the information source and the input means of the first shift register.

35 13. A device as claimed in claim 12, wherein the sampler is followed by an analog-to-digital converter.

14. A device as claimed in claim 1, for the transmission of binary information pulses, wherein the device constitutes a modulator for the binary information pulses.

40 15. A device as claimed in claim 14, wherein a code converter for establishing a binary code conversion is incorporated between the information pulse source and the first shift register.

16. A device as claimed in claim 14, adapted for amplitude 45 modulation, wherein the modulation elements in the nodes of the matrix network comprise AND-gates and the weighting devices connected to the output means of the AND-gates have transfer coefficients $C_{\nu\mu}$ in accordance with the equations

$$C_{\nu\mu} = \begin{cases} 4 \frac{\omega_g}{\omega_r} \cdot \frac{\omega_c}{\omega_\delta} \cdot \sin\left(\nu 2\pi \frac{\omega_g}{\omega_r}\right) \cdot \cos\left(\mu 2\pi \frac{\omega_c}{\omega_\delta}\right), & |\mu| < \frac{\omega_\delta}{2\omega_c} \\ 2 \frac{\omega_g}{\omega_r} \cdot \frac{\omega_c}{\omega_\delta} \cdot \sin\left(\nu 2\pi \frac{\omega_g}{\omega_r}\right) \cdot \cos\left(\mu 2\pi \frac{\omega_c}{\omega_\delta}\right), & |\mu| = \frac{\omega_\delta}{2\omega_c} \\ 0, & |\mu| > \frac{\omega_\delta}{2\omega_c} \end{cases}$$

$$60 \nu = 0, \pm 1, \pm 2, \dots, \pm n$$

$$\mu = 0, \pm 1, \pm 2, \dots, \pm m$$

65 in which ν is a shift register element of the first shift register reckoned from the center of said first shift register and with opposite sign on either side of said center, while μ is a shift register element of the second shift register likewise reckoned from the center of the second shift register and with opposite sign on either side of said second center.

70 17. A device as claimed in claim 14, adapted for vestigial sideband modulation, wherein the modulation elements in the nodes of the matrix network comprise AND-gates and the weighting devices connected to the output means of the AND-gates have transfer coefficients $C_{\nu\mu}$ in accordance with the 75 equations:

$$C_{\nu\mu} = \begin{cases} 4 \frac{\omega_g}{\omega_r} \cdot \frac{\omega_c}{\omega_\delta} \cdot \left[\text{si} \left(\nu 2\pi \frac{\omega_g}{\omega_r} \right) \cdot \cos \left(\mu 2\pi \frac{\omega_c}{\omega_\delta} \right) \pm \text{ci} \left(\nu 2\pi \frac{\omega_g}{\omega_r} \right) \cdot \sin \left(\mu 2\pi \frac{\omega_c}{\omega_\delta} \right) \right], & |\mu| < \frac{\omega_\delta}{2\omega_c} \\ 2 \frac{\omega_g}{\omega_r} \cdot \frac{\omega_c}{\omega_\delta} \cdot \left[\text{si} \left(\nu 2\pi \frac{\omega_g}{\omega_r} \right) \cdot \cos \left(\mu 2\pi \frac{\omega_c}{\omega_\delta} \right) \pm \text{ci} \left(\nu 2\pi \frac{\omega_g}{\omega_r} \right) \cdot \sin \left(\mu 2\pi \frac{\omega_c}{\omega_\delta} \right) \right], & |\mu| = \frac{\omega_\delta}{2\omega_c} \\ 0, & |\mu| > \frac{\omega_\delta}{2\omega_c} \end{cases} \quad (4)$$

$\nu = 0, \pm 1, \pm 2, \dots, \pm n$

$\mu = 0, \pm 1, \pm 2, \dots, \pm m$

in which ν is a first shift register element of the shift register reckoned from the center of said shift register and with opposite sign on either side of said center, while μ is a shift register element of the second shift register likewise reckoned from the center of said shift register and with opposite sign on either side of said second center.

18. A device as claimed in claim 14, adapted for single side-band modulation, wherein the modulation elements in the nodes of the matrix network comprise AND-gates and the weighting device is connected to the output means of the AND-gates have transfer coefficients $C_{\nu\mu}$ in accordance with the equations:

$$C_{\nu\mu} = \begin{cases} \frac{4}{\pi} \frac{\omega_g}{\omega_r} \cdot \frac{\omega_c}{\omega_\delta} \left[\frac{1 + \cos \left(\nu 2\pi \frac{\omega_g}{\omega_r} \right)}{1 - \left(2\nu \frac{\omega_g}{\omega_r} \right)^2} \cdot \cos \left(\mu 2\pi \frac{\omega_c}{\omega_\delta} \right) \pm \frac{\sin \left(\nu 2\pi \frac{\omega_g}{\omega_r} \right)}{1 - \left(2\nu \frac{\omega_g}{\omega_r} \right)^2} \cdot \sin \left(\mu 2\pi \frac{\omega_c}{\omega_\delta} \right) \right], & |\mu| < \frac{\omega_\delta}{2\omega_c} \\ \frac{2}{\pi} \frac{\omega_g}{\omega_r} \cdot \frac{\omega_c}{\omega_\delta} \left[\frac{1 + \cos \left(\nu 2\pi \frac{\omega_g}{\omega_r} \right)}{1 - \left(2\nu \frac{\omega_g}{\omega_r} \right)^2} \cdot \cos \left(\mu 2\pi \frac{\omega_c}{\omega_\delta} \right) \pm \frac{\sin \left(\nu 2\pi \frac{\omega_g}{\omega_r} \right)}{1 - \left(2\nu \frac{\omega_g}{\omega_r} \right)^2} \cdot \sin \left(\mu 2\pi \frac{\omega_c}{\omega_\delta} \right) \right], & |\mu| = \frac{\omega_\delta}{2\omega_c} \\ 0, & |\mu| > \frac{\omega_\delta}{2\omega_c} \end{cases}$$

$\nu = 0, \pm 1, \pm 2, \dots, \pm n$

$\mu = 0, \pm 1, \pm 2, \dots, \pm m$

in which ν is a shift register element of the shift register reckoned from the center of said shift register and with opposite sign on either side of said center, while μ is a first shift register element of the second shift register likewise reckoned from the center of said shift register and with opposite sign on either side of said second center.

19. A device as claimed in claim 14, adapted for phase modulation, wherein the device is formed as an amplitude modulator in which also the outputs of the shift register elements of the second shift register are connected through additional weighting devices to the combination device for compensating the carrier oscillation.

20. A device as claimed in claim 14, adapted for phase modulation, wherein the modulation elements in the nodes of the matrix network comprise modulo-2-adders and the weighting devices connected to the modulo-2-adders have transfer coefficients $C_{\nu\mu}$ in accordance with the equations:

$$C_{\nu\mu} = \begin{cases} 4 \frac{\omega_g}{\omega_r} \cdot \frac{\omega_c}{\omega_\delta} \cdot \text{si} \left(\nu 2\pi \frac{\omega_g}{\omega_r} \right) \cdot \cos \left[\mu 2\pi \frac{\omega_c}{\omega_\delta} \right], & |\mu| < \frac{\omega_\delta}{2\omega_c} \\ 2 \frac{\omega_g}{\omega_r} \cdot \frac{\omega_c}{\omega_\delta} \cdot \text{si} \left(\nu 2\pi \frac{\omega_g}{\omega_r} \right) \cdot \cos \left[\mu 2\pi \frac{\omega_c}{\omega_\delta} \right], & |\mu| = \frac{\omega_\delta}{2\omega_c} \\ 0, & |\mu| > \frac{\omega_\delta}{2\omega_c} \end{cases}$$

$\nu = 0, \pm 1, \pm 2, \dots, \pm n$

$\mu = 0, \pm 1, \pm 2, \dots, \pm m$

15 21. A device as claimed in claim 14, adapted for frequency modulation, wherein the device is formed as an amplitude modulator and that furthermore the information source is connected through an OR-gate to the first shift register, a sub-carrier pulse generator also being connected to said OR-gate, 20 the pulse repetition frequency of said subcarrier pulse generator being greater than or equal to twice the clock frequency of the information pulses.

22. A device as claimed in claim 14, provided with a plurality of matrix networks in which the nodes incorporate modulation elements, wherein the shift register elements of one of the shift registers are connected to the modulation element of dif-

45 ferent matrix networks.

23. A device as claimed in claim 22, for the transmission of binary information pulses originating from two information sources with orthogonal modulation, further comprising a second information source, a third control generator, a third shift register coupled to said second information source and having a plurality of shift register elements whose contents are shifted by said third control generator, a second matrix network having columns and rows which have nodes comprising modulation elements, means to couple respectively said columns of said modulation elements of said second matrix network to said shift register, means to couple respectively said rows of said modulation elements of said second matrix network to the shift register elements of said second shift register, and a second plurality of weighing devices coupling said modulation elements of said second matrix network to said combination devices.

24. A device as claimed in claim 22, wherein the modulation elements in the nodes of the two matrix networks comprise AND-gates and the weighting devices of the first matrix network connected to the AND-gates transfer coefficients in accordance with Claim 16, and that the weighting devices of the second matrix network have transfer coefficients $C\phi\lambda$ in accordance with the equations:

$$C_{\kappa\lambda} = \begin{cases} 4 \cdot \frac{\omega_y}{\omega_r} \cdot \frac{\omega_r}{\omega_\delta} \cdot \text{si}\left(\kappa 2\pi \frac{\omega_y}{\omega_r}\right) \sin\left(\lambda 2\pi \frac{\omega_r}{\omega_\delta}\right), & |\lambda| < \frac{\omega_\delta}{2\omega_c} \\ 2 \cdot \frac{\omega_y}{\omega_r} \cdot \frac{\omega_r}{\omega_\delta} \cdot \text{si}\left(\kappa 2\pi \frac{\omega_y}{\omega_r}\right) \sin\left(\lambda 2\pi \frac{\omega_r}{\omega_\delta}\right), & |\lambda| = \frac{\omega_\delta}{2\omega_c} \\ 0, & |\lambda| > \frac{\omega_\delta}{2\omega_c} \end{cases}$$

$$\kappa = 0, \pm 1, \pm 2, \dots, \pm k$$

$$\lambda = 0, \pm 1, \pm 2, \dots, \pm l$$

in which λ is a third shift register element of the shift register reckoned from the center of said shift register and with opposite sign on either side of said center, while κ is a shift register element of the first shift register connected to the carrier oscillator likewise reckoned from the center of said shift register and with opposite sign on either side of said second center.

25. A device as claimed in claim 14 wherein at least three shift register elements are connected to the modulation elements in the nodes of a matrix network, with which shift register elements multiple modulation is obtained.

26. A device as claimed in claim 1, wherein the pulses applied to the input of a shift register are simultaneously delayed in a single shift register over a period T_1 multiplied by an in-

teger ν and over a period T_2 multiplied by an integer ϕ , the ratio T_1/T_2 being rational.

27. A device as claimed in claim 14 wherein the device for single sideband modulation is provided with a third shift register and a subcarrier oscillator for generating a subcarrier oscillation whose frequency is equal to one quarter of the clock frequency of the information pulses, while the device is furthermore provided with a single matrix network whose modulation elements are each connected to a shift register element of the three shift registers.

28. A device as claimed in claim 1, wherein each modulation element is connected to two shift register elements of the second shift register and to one shift register element of the first shift register.

29. A device as claimed in claim 1, wherein a periodical series of rectangular pulses of pulse repetition frequency f_r is applied by the information source to the modulation elements in the nodes of the matrix network, the output circuit of each modulation element being connected through different weighting devices to different combination devices each supplying a frequency $f_c \pm n f_r$.

30. A device as claimed in claim 29, wherein only every other shift register element is connected to a modulation element in the matrix network when pulses are applied to the shift registers whose duration is equal to half the pulse repetition period, and when a ratio given by $(2m+1) : 1$ with $m=2, 3, 4, 5 \dots$ exists between the shift frequency and the double pulse repetition frequency.

31. A device as claimed in claim 1, 1, wherein the information source also operates as a carrier oscillator so as to generate higher powers of the information pulses.

32. A device as claimed in claim 1, wherein the device is integrated in a semiconductorbody.

UNITED STATES PATENT OFFICE
CERTIFICATE OF CORRECTIONPatent No. 3,665,314Dated May 23, 1972

- 1 -

Inventor(s) PETER LEUTHOLD

It is certified that error appears in the above-identified patent and that said Letters Patent are hereby corrected as shown below:

Column 3, line 42, change "f_η" to --f_η--;

line 47, change "f_η" to --f_η--.

Column 4, line 26, change "C₁₁₇ 5-5" to -- -C₊₅₋₅--;

line 57, change "IS" to --is--;

Column 7, lines 13 and 14, change "- $\frac{1}{2} \frac{\omega_c}{\omega_s}$ " to -- - $\frac{\omega_c}{\omega_s}$ --.

Column 8, line 17, change "C_{Xη}" to --C_{Xλ}--.

Column 10, line 18, change " $\widetilde{H}_1(\omega)$ and $\widetilde{H}_2(\omega)$ " to

--H₁(ω) and H₂(ω)--;

line 69,

change " $\begin{cases} g \omega_g \\ -\omega_g \end{cases}$ " to -- $\begin{cases} \omega_g \\ -\omega_g \end{cases}$ --.

Column 11, line 42, change "f₁₂" to --f₁₃--;

line 66, change " $\frac{\omega_d}{2\omega_c}$ " to -- $\frac{\omega_d}{2\omega_c}$ --.

Column 12, line 43, change "1- $\left(2v \frac{\omega_g}{\omega_f}\right)$ " to

-- 1- $\left(2v \frac{\omega_g}{\omega_f}\right)^2$ --.
